LOWELL C. BLOMSTROM, OF DETROIT, MICHIGAN, ASSIGNOR TO FEDERAL MOGUL CORPORATION, OF DETROIT, MICHIGAN, A CORPORATION OF MICHIGAN

MEANS FOR MOUNTING BEARINGS ON ARBORS IN MULTIPLE

Application filed August 6, 1937. Serial No. 311,088.

This invention relates to means for mounting in multiple, for either continuous or rapidly successive grinding or similar shop operations, either whole bearings or half bearings, and has for its object an improved organization of parts by means of which the individual articles to be worked upon may be rapidly and firmly clamped about or released from a holding arbor designed to be positioned in suitable relation to the cutting tool or tools.

In the drawings:

Figure 1 is an elevational view lengthwise of the arbor with the supporting frame for convenient assemblage purposes shown in dotted lines.

Figure 2 is a sectional elevational view taken from the same position as Figure 1.

Figure 3 is an end elevational view of the arbor in relation to the support whose position is indicated in dotted lines.

Figure 4 is a cross sectional view taken along the line 4—4 of Figure 1.

Figure 5 is a similar view taken along the line 5—5 of Figure 1.

Figure 6 is a sectional detail showing a desirable though not indispensable variation in the angularity of the engaging edge of one of the clamps.

Figure 7 is an elevational view partly in section of a modified form of clamp, showing the possible engagement of its holding faces with a terminally flanged bearing shell.

12 represents a bench assemblage frame, in the suitably recessed top portion of whose uprights are designed to be temporarily rested and held against rotation the ends 14 of the bearing arbor 13. The base member of this arbor consists of a cylindrical or solid shaft member, provided at its ends just inside the tips 14 with screw threaded surfaces 15, the pitch of the threading at one end being of opposite inclination to that on the other end. Overengaging these threaded surfaces of the arbor are terminal clamp members 16 provided with internal threadings of complementary pitch, each of these clamp members being adapted to be rotatably actuated about the arbor 13 by means of a wrench or similar tool placed upon the wrench holds

17. As brought out particularly in sectional Figure 2, the inwardly facing or bearing edges of these clamping members are preferably bevelled or similarly contoured, as at 18, to provide for a seizing overengagement with the adjacent bevelled edges of full bearings 19 or half bearings 20 which may be mounted upon the arbor. The length of the arbor may be such that any desired number of bearings or half bearings can be clampingly mounted in position thereon for presentation either consecutively or successively to the action of a machining tool upon their outer curved surfaces, the individual bearings being suitably spaced from one another as well as clampingly held by the alternating collars 21.

The bare arbor which is to be loaded first has one of the terminal clamping members removed from its end only if cylindrical bearing shells are to be mounted thereon, and there are then slipped or positioned over it, in alternation, bearing shells and these holding collars, the first bearing shell, as for example, that occupying the space Y, being pushed along the arbor until it engages the bevelled holding edge 18 of that one of the terminal clamping members still remaining thereon. One of the collars, as 21, is then slipped onto the arbor and pushed into engagement with the opposite edge or end of the bearing shell or pair of bearing shells from that engaged by the bevelled edge 18 of the holding clamp. Then another shell, as for example Z, is slipped over the arbor and against the opposite end or edge of the collar 21 from that which engages the first inserted shell Y, then another bearing shell is slipped over the arbor, and so on until it has been loaded to its full capacity, when the primarily removed second terminal clamp member is replaced in position, and by means of wrench hold action as described, the several arbor-supporting elements are forced into intimate and tightly holding association with one another, the rotative movement of the arbor being prevented as already described by its engagement with the squared recess in the top of the frame 12. The arbor with its load is then removed and placed in

a suitable storage receptacle for set up and insertion in proper relation to a grinding or cutting tool by the operator of such a machine. The apparatus herein described is 5 equally available for holding half bearings in position on the arbor for grinding; in such case, the preliminary removal of one of the terminal clamping members is unnecessary. This possibility and the resultant 10 structural modifications being brought out in Figures 2, 4 and 5. Many of these half bearings are actually and intentionally slightly less than a full half circle. In other words, when two of them are assembled about 15 the body of the arbor, as brought out in Figure 4, there are slight spaces, as X, between their meeting edges; but the clamping effect of the holding collars 21 or as to the bearings at either end of the group mounted upon the 20 arbor, of the bevelled edges 18 of the terminal clamp members, is so tight that they are firmly held in position so that the machining of their outer surfaces can be proceeded with in substantially the same manner as in the case of the whole bearings already described.

In case, however, only half bearings are to be mounted in each of the spaces intermediate the holding collars 21, it is advisable 30 to provide means for halting rotative movement of the half bearing about the arbor under the intense fractional actuation of the grinding tool as it is applied to the outer surface of the bearing. To this end the arbor 35 is provided at suitable intervals along its length with transverse holes or bores 23 and 24, located axially perpendicular to one another. In one of these, as 23, engages the slightly movable detent piece 25, which is 40 provided with marginal lips 26, and which is adapted to be actuated limitedly across the axial line of the arbor as a whole by action of the screw 27. Since this latter, in addition to this holding against rotation, is held by 45 the engagement against its marginal edges of two of the various holding elements already described, the bearing is very efficiently held against undesired rotation; and when the detent 25 is driven to its seated or holding 50 position, the outer corner or tip of its flange 26 lies far enough within the ring of possible cut by the grinding apparatus so as not to be touched thereby. It will be noted in Figure 2 that the bearings *a* and *b* there represented are either full bearings or pairs of half bearings such as are illustrated in sectional Figure 4, thus completely encircling the arbor, and not requiring the action of the 55 detent piece 25 and screw 27, whereas the bearings *c*, *d* and *e*, similarly shown in dotted lines, only extend about the lower half of the arbor's surface. The position of the straight edges of these half bearings relatively to the arbor as a whole is indicated

by the full lines 26 on those portions of Figure 1 representing the position of bearings *c*, *d*, and *e* thereon, as well as being suggested by the absence of the dotted line representation of the bearing shell at the bottom 70 of Figure 2, opposite the half bearings *c*, *d* and *e*.

To compensate for possible variations in the angularity of the bevelled edges of the bearing shells, as a result of a previous machining operation not here in question, it is often advisable to provide the bevelled edges 18 of the terminal clamping members with a slightly different angular inclination from the expected bevelled edge of the shells, so 80 that in case of any variation therefrom, the relatively hard metal formation of the clamping members and the collars 21 of which it is composed will very slightly dig into the relatively soft metal of the bearing shell sufficiently, though non-injurious to afford firm holding engagement of the bearing shell on the arbor. This is brought out at 28 and 29 in Figure 6.

The idea mentioned in the paragraph just preceding, as to the slight possible cutting in of the hard metal of the bearing clamp as contrasted with the soft metal of the bearing shell, is illustrated as to a possible further modification of construction in Figure 7, 90 wherein the companion members 30 and 31 of a single rather than multiple shell-handling device are provided with suitable bevelled faces, as 32 and 33, adapted to be pressed into clamping engagement with the flanged edges 34 of a bearing shell 35 which thus differs from the plain bearing shell 19, illustrated in Figures 1 and 2. The lengthwise projection of the clamp piece 31 along the arbor 36 is provided for by a wrench hold 100 37 and screw threadings 38 similar to those described as to the form of construction in Figures 1 and 2. The intermediate space on the outer surface of the bearing shell whose grinding is to be undertaken is not, however, overengaged by the bevelled flanges 32 and 33 in a way or to an extent that will 105 prevent adequate access of the grinding tool to that portion of the shell's surface bounded by the projecting or flanged end portions. 110

While it will be apparent that the illustrated embodiments of my invention herein disclosed are well calculated to adequately fulfill the objects and advantages primarily stated, it is to be understood that the invention is susceptible to variation, modification and change within the spirit and scope of the subjoined claims.

What I claim is:

1. In combination with an arbor provided with oppositely threaded portions adjacent its ends, a supporting frame provided with terminal abutments having seats wherein the ends of said arbor may be temporarily and non-rotatably positioned, a plurality of an- 125

- nular members adapted to be positioned about said arbor in alternating relation with bearing shells whose firm positioning for machining treatment is desired, and threaded 5 terminal clamp members operatively engaging the correspondingly threaded portions of said arbor and adapted to be moved toward and away from one another by induced rotative actuation lengthwise of said arbor, thereby forcing them and said annular members 10 into marginal holding engagement with the edges of their adjacently positioned bearing shells, and holding the latter in temporarily immobile relation about the arbor.
- 15 2. In combination with a terminally threaded arbor and complementarily threaded clamping members operatively positioned thereon, the inwardly facing edges of said clamping members being undercut from true 20 right angularity to provide diversely contoured frictional surfaces from the marginal edge portions of the blanks which they are adapted to engage, a plurality of annular shell-engaging members removably engaging 25 over the intermediate portion of the arbor in alternating relation with bearing shells, with the ends of which they are adapted to be forced into firm holding relation by the induced axially lengthwise movement of said 30 clamping members toward one another and against the overengaged marginal edges of the adjacent blanks upon the threaded ends of the arbor.
3. In combination with an arbor and removable clamping members operatively engaging the end portions thereof, a plurality of annular members adapted to be positioned on said arbor in alternating relation with cylindrical or semi-cylindrical bearing shells 35 positioned thereabout, all of which are adapted to be forced into tight engagement with one another by the actuated movement of one of said clamping members toward the other clamping member, and means carried by said 40 arbor and adapted to be selectively forced into operative relation with half bearing shells positioned on the arbor, whereby, in addition to the described clamping of their terminal edges, they are held against rotative movement about the arbor.
4. The combination, with an arbor member, and removable clamping members operatively engaging the end portions thereof, of a plurality of annular members adapted to 45 be positioned about the intermediate portion of said arbor member in alternating relation with bearing shells also positioned thereon, all of the elements positioned on said arbor 50 being adapted to be forced into temporarily immobile relation to one another by the actuated movement of one or the other of said clamping members along the arbor toward the other clamping member, and means for holding such of the bearing shells as are semi- 55 cylindrical against rotative movement relatively to the arbor.
5. In combination with an arbor provided with removable terminal clamping members capable of limited operative movement 60 lengthwise thereof, annular elements adapted to be arranged along the intermediate portion of said arbor in alternating relation with bearing shells positioned thereupon, all of such elements being adapted to be forced into close marginal engagement with those adjacent on either side by the actuated movement of one of said clamps along said arbor toward the other clamp member, and means carried by said arbor and adapted to be moved into position of operative engagement with such of the bearing shells as are semi-cylindrical, whereby such shells are held 65 against rotative movement about said arbor. 70
6. In combination with an arbor having threaded end portions, terminal clamping members operatively engaging the threaded ends of said arbor, and a plurality of annular members slidably engaging about the intermediate portion of said arbor, the inwardly facing edges of said clamping members and each edge of each annular member being adapted to operatively engage the edge portions of half-bearing shells interposed between them on the arbor, all of the parts thus 75 assembled on the arbor being adapted to be forced into operative engagement with one another by the suitably actuated movement of one of said terminal clamping members 80
7. In combination with an arbor about whose central portion a plurality of bearing shells and clamping rings are adapted to be alternatingly positioned, means operatively connected with the unoccupied end portions 85 of said arbor whereby the adjacent edge portions of the several alternated elements positioned thereon may be forced into firm engagement with one another, and normally inactive means adapted to act transversely of the axis of the arbor whereby such of said bearing shells as are only of substantially semi-circumferential extent are also held against rotative movement relatively to the arbor while being acted upon by an external 90 machining element.
8. In combination with an arbor, terminally positioned members capable of limited movement lengthwise thereof, a plurality of annular clamping members adapted to be projected by the actuated movement of said terminally positioned members into marginal holding engagement by their edge portions with the corresponding and adjacent portions of bearing blanks alternated therewith along said arbor, and supplemental holding members contained within the body of the arbor and adapted to move transversely of the axis thereof, adapted to be active only 95 when the bearing blanks positioned opposite 100
- 105 110 115 120 125 130

them are of substantially semi-cylindrical contour, to hold such blanks against rotative movement about the arbor while being operated upon by an external machining element.

5 9. In combination with an arbor provided with threadings adjacent its ends, terminal clamp members operatively engaging said threaded portions of said arbor, the interiorly facing edges of said clamp members being overengagingly contoured for seizure of the adjacent marginal edges of the end units of a group of bearing shells positioned about said arbor, and annular spacing members positioned on said arbor in alternating relation with said bearing shells and adapted to marginally engage said bearing shells when forced into close association with one another by actuated movements of said terminal clamp members toward one another along

20 said arbor.

10. The combination, with an arbor having threadings adjacent its ends, of a series of annular spacing members positioned about the intermediate portion of the arbor in alternated relation with a group of bearing shells whose firm temporary tenure while being machined is desired, and a pair of terminal clamp members provided with threadings which effect an adjustable operative relation between each member and its corresponding threaded portion of the arbor, whereby the alternated spacing members and bearing shells positioned upon said arbor may be forced into non-rotatable marginal engagement with one another by the manually actuated movement of said clamp members toward one another along said arbor.

11. In combination with a terminally threaded arbor member and a pair of correspondingly threaded terminal clamp members operatively positioned thereon in position of potential movement toward and away from one another therealong, the interiorly facing ends of said terminal clamp members being formed for overengaging seizure of the adjacent marginal edges of the adjacent members of a group of bearing shells temporarily positioned upon said arbor, and a series of annular spacing members carried by said arbor in alternating relation to the bearing shells, each of said recited parts upon said arbor being adapted to be forced into non-rotatable marginal engagement with those adjacent it by the actuated movement of

55 said terminal clamping members toward one another.

In testimony whereof I sign this specification.

LOWELL C. BLOMSTROM.
